CLAIM

The ornamental design for a divot tool, as shown and described.

DESCRIPTION

FIG. 1 is a front perspective view of a divot tool, according to the present invention;

FIG. 2 is a rear perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken line showing of the divot tool is for the purpose of illustrating portions of the divot tool which form no part of the claimed design.

1 Claim, 3 Drawing Sheets(56)
